WILLIAM J. BAUER, OF NEW YORK, N. Y.

COLLAPSIBLE TABLE

Application filed March 22, 1929. Serial No. 349,095.

The invention relates generally to furniture construction, and more especially to a supporting member of the collapsible type, for example, a table having supporting legs which are designed to fold underneath said table when the same is not in use and to be extended substantially at right angles to its top portion when it is desired to place said table in service.

10 It has for its object a simple and inexpensive construction of furniture structure of this character which may readily be manipulated in erecting the same as well as in collapsing said article. A further object of the invention resides in a furniture structure wherein the supporting legs may securely be located in position to rigidly sustain the top or platform portion thereof. A still further object of the invention resides in the novel 15 leg-supporting bracket which may, also, be arranged to carry reinforcing elements for the top or platform member of the structure.

To this end, there is provided a plurality 20 of supporting brackets attached to the top or platform portion of the structure, which brackets are designed to pivotally support the leg members to thus connect the same with the top. Each leg member, moreover, carries means adapted for locking engagement 25 in its respective pivoting bracket to hold the structure as a whole against collapse. These brackets, furthermore, may be provided with a wing to which is then rigidly secured diagonal braces or reinforcing elements 30 immediately beneath the top or platform portion to sustain the same.

The nature of the invention, however, will best be understood when described in connection with the accompanying drawings, in 35 which:

Fig. 1 is a perspective underneath view showing a table member, as one embodiment of my invention, in the erected position.

Fig. 2 is a fragmentary longitudinal section illustrating the manner of maintaining the table supporting legs in elevated position, the dotted line indicating the extended position.

Fig. 3 is a fragmentary transverse section 50 thereof taken on the line 3-3, Fig. 2 of

the drawings, and looking in the direction of the arrows.

Figs. 4 and 5 illustrate respectively in side and front elevation the upper portion of a supporting leg and pivoting bracket therefor. 55

Fig. 6 is a perspective view of a holding bracket.

Fig. 7 is a perspective underneath view showing a modified form of table member and in the erected position. 60

Fig. 8 is a fragmentary detail vertical section illustrating the manner of maintaining the table-supporting legs thereof in supporting position.

Fig. 9 is a fragmentary vertical section taken on the line 9-9, Fig. 8 of the drawings, and looking in the direction of the arrows. 65

Fig. 10 is a perspective view of the modified form of holding bracket.

Fig. 11 shows in elevation and on an enlarged scale the locking lever employed for securing a supporting leg member to its holding bracket. 70

Referring to the drawings, 10 designates 75 an enclosing member for affording a frame, for example of square or other desired shape, and adapted to receive the top or platform element 11. A finishing strip 12 may also be provided about the frame 10, which frame is made of sufficient depth to conceal or retain therein, when the table is collapsed, the supporting leg members 13. The latter are, preferably, hollow as of tubular metal, being designed to support said top when the table is erected for use, as indicated in Fig. 1. 80

In this condition, the legs 13 extend substantially at right angles to said top 11 being arranged to swing freely downwardly therefrom or, rather, from the frame 10 to which they are pivotally attached. This attachment may be effected, for example, by means of brackets, such as the U-shape retaining bracket 14, rigidly secured in the respective corners of the frame and supporting a pivot pin or rivet 15 passing through the upper end of a leg pivotally fitted therein to permit the same to swing freely thereon and downwardly from the undersurface of the frame or platform portion 11 of the table. 85

The said pin 15 is arranged, also, for a 100

limited longitudinal movement relatively to a corresponding leg member, as by providing a pair of slots 16 in its opposite sides at the upper end and in which the pin is drawn normally to the bottom thereof under the action of a spring 17 connected to the said pivoting pin 15 and to a further pin 18 mounted below the slots in the leg member and transversely of the same. A said leg is provided, also, with pins 19 projecting laterally from the side wall thereof and adapted to lock in slots 20 provided in the side walls of a corresponding U-shape bracket 14.

These slots extend inwardly from the corresponding lower edges of a bracket; and the bracket itself is, furthermore, provided at its side walls with projecting portions having the respective cam edges 21, and also with the fingers 22, the latter extending inwardly and being turned over the corresponding face of the hollow leg member which, as shown, is square in section.

If it be desired to fold the leg member up into position beneath the table top 11, it is necessary merely to pull outwardly, against action of spring 17, the particular leg member so that its pins 19 will clear their respective slots 20 of the bracket, and thereupon swing the leg member upwardly and into horizontal position until stopped by the inwardly projecting fingers 22. These fingers also prevent contact of a leg member with the undersurface of a top and thus reduce the danger of marring the finish of the same, as by scratching or knocking off the paint therefrom. Moreover, it will be observed that the pins 19 are then also slightly beyond the high point of the respective cam surfaces or edges 21 (as indicated by the position shown in dotted lines, Fig. 4) so that any tendency of a leg member to drop downwardly when once in folded position is obviated; and the table may be freely carried about without danger of these leg members dropping from their position. To restore the legs to a vertical position in erecting the table, it is necessary merely to exert sufficient force thereon to turn the same downwardly, the pins 19 riding over the cam surfaces 21 until they eventually drop into the slots 20, being drawn thereto by the spring 17.

The U-shape retaining brackets may, also, be provided with a diagonally directed wing 25 to which are attached reinforcing members or braces 26 extending diagonally across the underside of the top and immediately beneath the same to sustain the top 11.

When a solid type of leg member is desired, this may be secured by similarly mounting the leg members. For example, reference being had to Figs. 7 to 11, 30 designates the enclosing member for affording a frame of the desired shape adapted to receive the top or platform 31, with finishing strip 32 about said frame. The supporting

legs 33 for the table are pivotally mounted in U-shape brackets 34. These brackets are, as in the previous embodiment, rigidly secured in the respective corners of the frame as by a supporting pivot pin or rivet 35 which passes also through the upper end of a leg fitted for pivotal mounting therein.

When the legs are then extended to support the top, provision is made for retaining them against movement relatively to their carrying bracket member 34 as through a locking lever 36 adapted for locking engagement in the corresponding bracket, each of said leg members pivotally carrying one of said locking levers. It is preferred to pivot a lever to its respective leg member as by a shouldered screw 37 passing therethrough and into the leg member, said screw having an unthreaded cylindrical portion 38 designed to fit a corresponding opening 39 of a plate 40 set into the leg member flush with its surface. Normally, a lever 36 will be positioned substantially in the plane of a leg member under the action of gravity; and, after the said leg members are extended, it is necessary in order to effect the locking engagement merely to manually swing said levers about their respective pivoting pins 37 and upwardly to fit in a slot 41 of the pivoting bracket.

Levers 36, moreover, are provided each with a holding tooth 42 so that when the lever is elevated for engagement with the bracket, tooth 42 may exert pressure against a corresponding side wall of a bracket member 34 to exert a friction hold thereon. This will serve to prevent the various legs from swinging outwardly as the corresponding lever 36 is temporarily locked transversely of a said leg in the slot or notch 41 provided in the holding bracket 34; and it is preferred, also, to provide the opposite end of the lever with a nose 43 to fit into a further and longer slot 44 in the opposite wall of the bracket 34, both of the slots 41 and 44 being cut inwardly from the lower edge and in a direction to accommodate the oscillation of the lever 36.

In order to collapse the table, it is necessary then merely to depress the various levers from their position of engagement with the corresponding pivoting brackets, whereupon the legs will be free to swing in said brackets 34 to a position within the frame 30 which is made of sufficient depth to substantially conceal therein the legs when thus collapsed.

A wing 45 may also be provided on the brackets for supporting diagonally disposed braces 46 immediately beneath the top 31, as in the previously described embodiment.

The constructions hereinbefore described provide for a very rigid support of the table when in erected position and admit also of its convenient collapse when it is no longer desired to make use of the table; and withal are of simple and relatively inexpensive design.

I claim:

1. A collapsible article of furniture, comprising a top or platform element, hollow legs for supporting the same and having longitudinal slots oppositely disposed in their side walls, a plurality of U-shape brackets attached to said top, a pin secured to each of said brackets and passing through the inner end of a leg and the slots of its side walls, a spring connecting the pin with the corresponding leg, and means carried by the leg for further engagement with said bracket for axially positioning the leg relatively thereto.
2. A collapsible article of furniture, comprising a top or platform element, legs for supporting the same and having longitudinal slots oppositely disposed in their side walls, a plurality of U-shape brackets, a pin secured to each of said brackets and passing through the inner end of a leg and the slots of its side walls, a spring connecting the pin with the corresponding leg, and laterally extending pins adapted to fit into further slots of the bracket extending inwardly from its lower edges.
3. A collapsible article of furniture, comprising a top or platform element, legs for supporting the same and having longitudinal slots oppositely disposed in their side walls, a plurality of U-shape brackets attached to said top, a pin secured to each of said brackets and passing through the inner end of a leg and the slots of its side walls, a spring connecting the pin with the corresponding leg, and laterally extending pins adapted to fit into further slots of the bracket and to ride over a cam edge of a corresponding side wall of said bracket to a position beyond its highest point.
4. A collapsible article of furniture, comprising a top or platform element, legs for supporting the same and having longitudinal slots oppositely disposed in their side walls, a plurality of U-shape brackets attached to said top, a pin secured to each of said brackets and passing through the inner end of a leg and the slots of its side walls, a spring connecting the pin with the corresponding leg, laterally extending pins adapted to fit into further slots of the bracket and to ride over a cam edge of a corresponding side wall of said bracket to a position beyond its highest point, and fingers inwardly turned from the side walls of a bracket to limit the inward movement of a corresponding leg.

In testimony whereof I affix my signature.
WILLIAM J. BAUER.
